UNITED STATES PATENT OFFICE.

GEORGE F. WEYMOUTH, OF DRESDEN, ASSIGNOR TO HIRAM HOLT, OF WILTON, MAINE.

HAY-KNIFE.

SPECIFICATION forming part of Reissued Letters Patent No. 10,715, dated April 20, 1886.

Original No. 112,400, dated March 7, 1871; Reissue No. 10,072, dated April 4, 1882. Application for reissue filed March 26, 1886. Serial No. 196,740.

To all whom it may concern:

Be it known that I, GEORGE F. WEYMOUTH, of Dresden, in the county of Lincoln and State of Maine, have invented a new and useful 5 Knife for Cutting Hay; and I do hereby declare that the following is a full and exact description thereof, reference being had to the accompanying drawing, and to the letters of reference thereon.

10 My invention consists of a long flat piece of steel in the shape of a sword, excepting the handles, with little knives on one edge, from the handle C to the point, the two handles C' standing out on one side, with which I thrust 15 the knife A perpendicularly into the hay, working it up and down as I would a saw.

To enable others skilled in the art to make and use my invention, I will proceed to describe its construction and operation.

20 I make my knife about one inch in width and one-fourth inch in thickness at the handles, and quite thin at the point, crooked edge-

wise like a broadsword with tooth-like knives B, about an inch long on the outer edge or curve, their points inclining toward the point 25 of the knife, as may be seen in the drawing, making a part of this specification, in which is represented the whole knife, which I call the "saw-knife." It may be any length required.

30 The purpose of the inclination of the knife-teeth or little knives is that they may feed themselves.

What I claim as my invention, and desire to secure by Letters Patent, is—

35 The improved hay-knife above described, consisting of the curved blade A, having knife-edged serrations B, and handles C C', placed as shown, all substantially as specified.

GEO. F. WEYMOUTH.
